MAGNETIC SPEAKER

Walter J. Paredes, Chicago, Ill., assignor to Ar-
lavox Manufacturing Company, a corporation
of Illinois

Application April 7, 1937, Serial No. 135,575

5 Claims. (Cl. 179—119)

This invention relates to an improved magnetic speaker, and more particularly to the driving unit for the diaphragm thereof.

One feature of this invention is that it provides an improved speaker of the magnetic type; another feature of this invention is that the number of parts and the number of assembly operations required are reduced; still another feature is that improved means are provided for 10 adjusting the neutral position of the driving armature; yet another feature is a simplified mounting plate, field assembly, and housing construction in the driving unit of the speaker; other features and advantages of this invention 15 will be apparent from the following specification and the drawings, in which:—

Figure 1 is a side elevation of a speaker embodying this invention; Fig. 2 is a plan view of the same speaker; Fig. 3 is a vertical sectional view thereof; Fig. 4 is a transverse sectional view along the line 4—4 of Fig. 3; and Fig. 5 is a view along the line 5—5 of Fig. 3.

The driving means for the diaphragm of a magnetic speaker must include a permanently magnetized unit of some kind to furnish a field, and a motor unit comprising pole pieces, a field coil and generally a rockable armature. Present day competition in the field of table sets, automobile radios, and the like make it necessary to 20 turn out a speaker which retains desirable power, sensitivity and fidelity characteristics and yet may be produced with a minimum of parts, waste metal, and assembly operations. The present invention provides an improved driving portion for 25 a magnetic speaker which achieves this object.

Where a rockable armature has a portion thereof extending outwardly between two pole pieces rather close to each other, it is necessary to properly center this armature after assembly 30 of the speaker in order to insure the maximum desired motion of the armature without striking either of the pole pieces. The speaker disclosed herein achieves this object by the provision of an improved guide member adapted to vibrate with 35 the armature, adjustable from without the driving unit housing after the complete speaker has been assembled.

In the particular embodiment of this invention disclosed herein a basket or frame 10 of conventional type serves to carry a diaphragm 11 here illustrated as a paper cone, although it may be of any other type. The frame also serves as a mounting for the driving or vibratory assembly within the housing 12. The cone 11 is 45 here shown as glued to the annular edge of the

frame 10, and as having an annular washer 13 of cardboard or similar material on the other side thereof to enable vibration of the cone when the speaker frame is mounted on a baffle-board or in a cabinet.

The driving assembly comprises a magnet unit 14; a motor unit comprising two substantially U-shaped pole pieces 15 and 16, a field coil 17 lying within the closure formed by these pole pieces, a rockable armature 18, and a pin 19 furnishing a driving connection between the armature and the cone; a tensioning or guide means 20 adjustable by means of the stud 21; top and bottom plates 22 and 23, respectively, and a substantially cylindrical housing member 12 of non-magnetic material.

The magnet unit 14 consists here of a rectangular block of permanently magnetized material, preferably of the recently discovered nickel aluminum alloy type having very high magnetic strength per unit of cross-sectional area. The top and bottom plates 22 and 23 and the pole pieces 15 and 16 are of magnetic material, such as steel or some other ferrous metal, and a strong field is thus formed across the openings between 25 the two pole pieces. The armature 18 is of the flat plate type lying principally within the pole pieces, with a section projecting outside of the pole pieces to furnish a connection with the driving pin 19, and is mounted at the center by the 30 two pins 24 and 25 to permit it to rock about an axis passing through these pins. The spacers 26 provide a form or spool for the field coil 17 and also keep the pole pieces separated the desired amount. The presence of an oscillating 35 current in the field coil, furnished by the output of a radio receiver, or the like, sets up corresponding electrical effects in the armature which interact with the field between the pole pieces to cause the armature to rock back and forth and 40 drive the diaphragm 11 in mechanical oscillations which correspond substantially to the current input.

As will be noted particularly from consideration of Fig. 3, the top and bottom plates 22 and 45 23 are pressed or stamped to form shallow sockets 27, 28, 29 and 30. The sockets 27 and 29 are adapted to receive opposite ends of the magnet unit 14 while the sockets 28 and 30 similarly receive opposite ends or pole pieces of the motor 50 unit. The assembly is so made that the top and bottom plates are urged together to grippingly engage the opposite ends of the magnet and motor units, and to hold them in proper place therewithin solely by this frictional engagement.

The frame 18 is provided at the upper part thereof with an annular flange 31 adapted to form a support on which the bottom plate 23 lies. The substantially cylindrical non-magnetic housing member 12 is provided with an inwardly turned flange 32 adapted to engage the top plate 22 and lock the entire assembly together when the housing member is fastened to the frame, as by the rivets 33. That is, the housing member 12 5 surrounds the two plates and prevents transverse movement, and the two annular flanges 31 and 32 serve to hold these plates in gripping engagement with the magnet and motor units, in turn held from any undesired movement both by the 10 frictional engagement and the fact that they are slightly sunk in the sockets in the plates. A very simple assembly may be followed, since it is only necessary to place the magnet unit and motor unit in the proper recesses in one of the plates, 15 20 place the other plate, on the opposite ends thereof, place the housing member 12 around both plates, and then lock the whole in place on the frame by the insertion and fastening of the rivets 33.

25 An improved tensioning and locking means 20, heretofore mentioned, comprises a portion adapted to be fastened to the bottom plate 23, as by the screws 34, an upwardly projecting portion 35 rising substantially vertically from the plate, 30 and a horizontal part substantially parallel to the plate comprising a base portion 36 and a flexible tongue member or portion 37. While the entire tensioning member is stamped out of a single piece of metal having the same gauge 35 throughout, the base portion 36 is so much broader than the tongue 37 that the entire flexing or vibrating is done by this tongue. That is, 40 since this tongue is fastened to the driving pin 19, as by soldering, it vibrates therewith, but this vibration is not transmitted to the base member, which remains practically stationary. The base member has the stud 21 threaded therein, this stud having the end of it bearing against the bottom plate 23 and being of such length that the head lies within the opening 38 in the top member 45 22, being flush with or below the outer surface of that plate. The spacing of the base portion 36 from the bottom plate 23 may be varied by rotation of the stud 21, conveniently accessible from 50 without the housing. The tensioning member is so stamped that its internal spring tension urges the base portion toward the bottom plate member, it being held away from that member by the interaction between the end of the stud and the plate. Thus the spacing of the base portion from 55 the bottom plate may be varied by rotation of the stud, and this in turn acts through the flexible tongue 37 to move the armature up or down, against any resistance present in its parts or the cone, to properly center it and have its neutral or inactive position equidistant from the pole

pieces. The presence of the flexible tongue, in addition to providing convenient adjustment of the neutral position of the armature and driving pin, provides a guide means preventing transverse vibration of the pin, and in other ways improving the quality of the output of the diaphragm. 5

While I have shown and described certain embodiments of my invention, it is to be understood that it is capable of many modifications. 10 Changes, therefore, in the construction and arrangement may be made without departing from the spirit and scope of the invention as disclosed in the appended claims, in which it is my intention to claim all novelty inherent in the invention as broadly as permissible, in view of the prior art.

I claim:

1. A vibrator assembly for a magnetic speaker of the character described, including: a motor 20 unit comprising pole pieces, a field coil, and a movable armature adapted to drive the diaphragm of said speaker; a magnet unit for energizing said pole pieces; and mounting means comprising a pair of plates of magnetic material 25 having sockets formed therein for receiving said units and grippingly engaging opposite sides thereof to furnish the sole support therefor.

2. A magnetic speaker of the character described, including: a frame; a diaphragm; a 30 plate of magnetic material mounted on said frame; a motor unit comprising pole pieces, a field coil, and a movable armature for driving said diaphragm; a unit for energizing said pole pieces, comprising a block of permanently magnetized material; a second plate of magnetic material; and a housing member of non-magnetic material on said frame having a flanged portion in engagement with said second plate, whereby said plates grippingly engage opposite 40 sides of said units to furnish the sole support therefor.

3. Apparatus of the character claimed in claim 2, wherein said plates have sockets formed therein for receiving said units.

4. Apparatus of the character claimed in claim 45 2, wherein said plates are round and said housing member is substantially cylindrical and adapted to closely surround said plates.

5. A vibrator assembly for a magnetic speaker of the character described, including: a motor 50 unit comprising pole pieces, a field coil, and a movable armature adapted to drive the diaphragm of said speaker; a magnet unit for energizing said pole pieces; and mounting means comprising a pair of plates for supporting said units solely by gripping engagement with opposite sides thereof, said plates being of magnetic material for completing the flux circuit between said pole pieces and magnet unit. 55

WALTER J. PAREDES. 60

for transmitting the impulses determined by the projections on the periphery of the then effective cam.

3. A telegraph transmitter including a plurality of key levers, an operating shaft, a plurality of cams secured to said shaft each of said cams having its periphery formed with projections corresponding to the individual impulses representative of the character to which said cam is allocated, means operated by the key levers for rendering said cams individually effective, a start cam also secured to said shaft and arranged to be effective prior to said plurality of cams, and means operated by the cams identified with the respective characters and the start cam for transmitting impulses in accordance with the effectiveness of said cams.

4. A telegraph transmitter including a plurality of key levers, an operating shaft, a plurality of cams secured to said shaft each of said cams having its periphery formed with projections corresponding to the individual impulses indicative of different characters, a universal bail, a start cam also secured to said shaft, a transmitting contact, and means operated by said bail through the operation of a key lever for rendering said start cam effective to effect through the operation of said contact the transmission of a start signal and thereafter one of said plurality of cams for the transmission of the character identifying impulses.

5. A telegraph transmitter including a plurality of key levers, an operating shaft, a plurality of character cams secured to said shaft each of said cams having its periphery formed with projections corresponding to the impulses individual to each character, a start cam also secured to said shaft, a transmitting contact, means common to the cams identified with the character and the start impulses, and means operated by said key levers for rendering said start cam and said character cams effective through said common means on said contact successively to effect the transmission of a start impulse followed by a series of character impulses.

6. A telegraph transmitter including a plurality of key levers, an operating shaft, a plurality of members carried by said shaft each of said members being identified with a particular character and arranged to control the transmission of impulses identified with the character allocated thereto, means for causing the transmission of a start impulse, means controlled by each of said key levers for rendering the member individual thereto effective for the transmission of impulses for the character thereof, and means operated in timed relation with respect to said members for insuring that a stop impulse will be transmitted at the end of transmission of the character impulses regardless of the continued operation of the key lever through the operation of which the start impulse was transmitted.

7. A telegraph transmitter including a plurality of key levers, a plurality of members, one for each character, impulses indicative of which are to be transmitted, a single transmitting contact, means operated by said key levers for rendering said members individually effective on said contact, an additional set of contacts connected in circuit with said transmitting contact, and means operated upon the depression of any of said key levers for operating said additional contacts.

8. A telegraph system including a receiver comprising starting and printing mechanisms, and a transmitter including a plurality of members one for each character, impulses indicative of which are to be transmitted, a plurality of key levers, means operated by said key levers for rendering said members individually effective, means common to said members and operated by each member for transmitting impulses in accordance with the operated member, means operative upon the depression of a key lever for transmitting a start impulse, and means effective in response to a start impulse for rendering said starting mechanism ineffective and said printing mechanism effective.
